UNITED STATES PATENT OFFICE.

JOSEPH C. LANDES, OF COLLEGEVILLE, PENNSYLVANIA.

AUTOMATIC GAS-CONTROLLER.

No. 858,878.

Specification of Letters Patent.

Patented July 2, 1907.

Application filed November 15, 1906. Serial No. 343,481.

To all whom it may concern:

Be it known that I, JOSEPH C. LANDES, a citizen of the United States, residing at Collegeville, county of Montgomery, State of Pennsylvania, have invented a new and useful Automatic Gas-Controller, of which the following is a specification.

My invention relates to means for automatically turning on and cutting off gas, at the burner therefor, and its object is to utilize the pressure of the gas at the generator, the gas works or elsewhere to accomplish the same.

In this end, I employ a movable device which is adapted to be influenced by such pressure, so as to close electric circuits whereby armatures or the like may be actuated to operate the valve of the burner in opposite directions for the respective purpose of so turning on and cutting off the gas.

Figure 1 represents a perspective view of a pressure-operated device for automatically igniting and extinguishing gas embodying my invention. Fig. 2 represents a vertical section thereof including an attached burner. Fig. 3 represents a section of a detached portion. Fig. 4 represents a side elevation of another detached portion.

Similar letters of reference indicate corresponding parts in the figures.

Referring to the drawings:—A represents a gas receiver which is closed at bottom and open at top and in which is telescopically fitted the rising and falling vessel B which is open at bottom and closed at top.

C designates the pipe for supplying gas to the burner D, the same having connected with it, at the coupling E, the pipe F which passes through the bottom of the receiver A into the vessel B and opens into the latter, said pipes F and C being subjected to the same pressure of gas admitted as at G from the gas generator or works, or elsewhere.

Supported on the vessel A, by the arms H or other suitable means is the circular run-way J which is composed of concentric plates K and L of electric-conductive material having their upper edges of spiral or inclined form, said run-way being also formed of two sections which are separated by the cross bar M of insulated material, and further separated as at M' so as to be insulated, it being noticed that the lower ends of the walls of one section terminate adjacent to the highest ends of the walls of the other section, said highest ends forming shoulders N adjacent to which is the ball P which is formed of electric-conductive material constituting a contact-piece or electrode adapted to roll on the spiral edges of the plates K and L and rest upon either end of side cross bar M.

The bar M' is connected with the vessel B at the top thereof so as to rise and fall with the same, said vessel being provided with, and guided true by, the eyes B'

through which pass the vertical rods Q, the latter being secured to the receiver A and provided at their upper ends with the nuts R, against which said eyes may abut to limit the ascent of the vessel B.

The burner D, has connected with its supporting frame, the separate magnets S and the armatures T, the latter being engaged with a valve U of said burner, so as to open and close the same as the respective armature is attracted, there being also provided the sparking device V for igniting the gas at the burner, but these features on the burner do not form the subject matter of any claim of invention, they being old in the art.

Separate wires or conductors W lead from the binding screws X on the exterior walls of the run way to a suitable battery, and separate wires or conductors Y lead from the binding screws Z on the interior wall of said run way to the magnets S, for purposes to be hereinafter specified.

The operation is as follows, the parts being in position as seen in Fig. 1. The gas is turned on when the pressure thereof raises the vessel B as a float and consequently the cross bar M. The ball P is then brought to the highest point of the section of the run way, in the present case the one at the right hand of said figure, and landed on the top edge of the plates of said section, whereby said plates as electrodes are placed in electric communication. This energizes the proper magnets S whereby the armature thereof is attracted, the movement of the latter then being communicated to the valve 75 U, thus opening the same, whereby the gas is turned on and a spark directed to the tip of the burner, thus igniting the gas and the light is thereby formed. The ball now rolls down the inclined surfaces of the section of the run-way again to the opposite end thereof, when it 80 again seats itself upon the cross bar, say at the left side thereof, the electric circuit as is evident now being broken. The pressure of gas which has been high, is lowered at the generator, works, etc., to normal, or whatever is required, when the vessel B descends, and 85 with it the cross bar and the ball thereon, the latter then resting on the cross bar. When it is desired to extinguish the light, the pressure of gas is again increased at the generator or works, when the vessel B is raised and the ball elevated with it and landed on the highest 90 end of the other section of the run-way, when the plates K and L of the latter are placed in electric circuit, and the wires or conductors thereof energizes the other magnet when the armature thereof is attracted and its movement operates the valve U to close it when the gas is 95 cut off and the light extinguished. Meanwhile the ball rolls down the inclined surface of the section, and leaving the same, seats itself upon the other end of the cross bar adjacent to the shoulder at the right hand of the other section, the electric circuit being again broken, 100

105

110

due to the new position of said ball. The pressure of the gas is then lowered when the vessel B descends, the ball remaining stationary until it is again time for lighting, when the gas is again turned-on under high pressure, and the operations hereinbefore stated are again repeated.

In order to prevent any short circuiting by the ball at the shoulders N, pieces J' of insulated material are placed on the bases J² of the sections of the run-way J at said shoulders, see Fig. 3, so that the ball or roller P may abut thereagainst, the effect of which is evident.

In some cases, there are attached to the sections N, N, adjacent to the circuit-breaking division or separation M, the switch N' for electrically connecting said sections to form a continuous circuit of the run-way when so required.

Having thus described my invention, what I claim as new and desire to secure by Letters Patent, is:—

1. In a device of the character stated, a gas receiver, a movable member adapted to be actuated by the pressure of the gas, electrodes one disposed in opposite direction to the other and primarily out of electric circuit and gravitating means operated by said member and adapted to be automatically placed from one to the other of said electrodes and to traverse the same for closing the circuit of said electrodes.
2. In a device of the character stated, a gas receiver, a movable member therein adapted to be actuated by the pressure of the gas, electrodes, one disposed in opposite direction to the other the same being primarily out of electric circuit, and a gravitating piece which is adapted to be placed by said member in contact with and to automatically gravitate over said electrodes and close an electric circuit.
3. In a device of the character stated, a gas receiver, a movable member therein adapted to be actuated by the pressure of the gas, electrodes one disposed in opposite direction to the other and primarily out of electric circuit, and a gravitating movable contact piece on said member adapted to be placed in contact with and to automatically gravitate over said electrodes and close an electric circuit.
4. In a device of the character stated, a gas receiver, a movable member therein adapted to be actuated by the pressure of the gas, a plurality of pairs of electrodes each primarily out of electric circuit, a gravitating movable contact piece carried by said member adapted to engage said electrodes and thereby close an electric circuit, said contact piece being adapted to automatically traverse each pair of a section of the electrodes and be automatically placed from one pair upon the other pair and successively close the circuit of each pair.
5. In a device of the character stated, a gas receiver, a float therein adapted to be actuated by the pressure of

gas, a gravitating movable piece carried by said float, a run way adapted to have said piece placed thereon by said vessel and electric conductors connected with said run way, said piece serving to place said conductors in an electric circuit.

6. In a device of the character stated, a gas receiver, a float therein adapted to be moved by the pressure of gas, electric conductors primarily out of electric circuit, and means, embodying a gravitating contact piece, for automatically placing said conductors in such circuit when said float is subjected to an increased pressure of gas.

7. In a device of the character stated, a gas receiver, a float therein adapted to be moved by the pressure of gas, conductors primarily out of electric circuit, a run way and a gravitating movable contact piece adapted to be placed by said float on said run way to gravitate thereon to form a circuit of said conductors.

8. In a device of the character stated, a gas receiver, a float therein adapted to be actuated by the pressure of gas, a plurality of electric conductors primarily out of electric circuit, sectional electrodes, each section having members provided with inclined surfaces, and a gravitating movable contact piece adapted to be placed by said float on the respective electrode.

9. In a device of the character stated, a gas receiver, a float therein adapted to be actuated by the pressure of gas, a transverse member thereon a plurality of conductors primarily out of electric circuit, sectional electrodes each section having members provided with inclined surfaces, and a gravitating movable contact piece normally supported by said transverse member and adapted to be placed by said float on the respective electrode.

10. In a device of the character stated, a gas receiver, a float therein adapted to be actuated by the pressure of gas, a run way formed of separate electrodes, electric conductors connected respectively with said electrodes and primarily out of electric circuit, and a gravitating movable contact piece adapted to be placed by said float on said electrodes and form a circuit of said conductors.

11. In a device of the character stated, a gas receiver, a member actuated by the pressure of gas, oppositely disposed inclined run ways forming electrodes, and a movable gravitating member normally out of the plane of said run ways and automatically placed thereon by change in the gas pressure.

12. In a device of the character stated, a gas receiver, a member actuated by the pressure of gas, oppositely disposed inclined run ways forming electrodes, a movable gravitating member normally out of the plane of said run ways and automatically placed thereon by change in the gas pressure, and means for automatically shifting said movable gravitating member from one run way to the other.
